MULTICELL SHUTTLE BOX FOR LOOMS

Carl J. Lindegren and Jacob B. Olch, Worcester,
Mass., assignors to Crompton & Knowles Loom
Works, Worcester, Mass., a corporation of Mas-
sachusetts

Application January 31, 1938, Serial No. 187,827

4 Claims. (Cl. 139—184)

This invention relates to a shuttle box made of pressed metal and it is the general object of the invention to provide a simple and durable shuttle box made of pieces of metal the major part of which are flat and assembled in such a way as to withstand the shock incident to the boxing of the shuttle.

Certain shuttle boxes are usable in different types of looms because of the fact that the shuttles are of substantially the same dimension. For this reason a shuttle box built to receive a relatively large silk shuttle, for instance, can also be used on a cotton loom employing a comparatively small cotton shuttle of the same size. In such cases, however, the lays of one type of loom will ordinarily be different from those of another type and as a result there is some variation in the size and form of the lay carried guides for the tongues of the multi-cell shuttle box. It is a further object of our present invention to permit the use of the greater part of an assembled sheet metal multi-cell shuttle box in different types of looms by providing removable tongue guides which can be adapted to the particular type of loom on which the shuttle box is to be used.

In this connection it is a more specific object of our present invention to adapt the removable tongue for reception of portions of the binder springs. The latter will be secured to welded parts of the shuttle box and by the construction just described the removable tongue will be relieved of any vibration incident to motion of the spring during shuttle boxing.

It is another object of our invention to extend the horizontal plates beyond the box mouth wall and secure to the extensions a vertical strip spaced from the mouth wall to limit outward motion of the binders. This strip is subjected to considerable vibration and strain during loom operation because of the constant striking thereof by the binder incident to shuttle boxing. In order therefore that this strip may be properly supported we provide additional blocks welded to the plates and projecting into holes punched in said strip. The latter is also welded to the blocks and the additional holding areas between the block and the strip provide a strong and durable attachment of the strip to the box. In many looms it is customary to make the inner ends of the binders narrower than the height of the shuttle and in order to prevent undue vertical play of the binder the aforesaid blocks define a shuttle binder and receiving compartment of less height than that of the shuttle.

In this way the blocks not only assist in holding the binder strip but also adapt the box to the use of binders constructed as described.

The binders are ordinarily pivoted on a vertical pin which extends along the front of the box near the outer end thereof. This pin is subjected to a strain similar to that imposed upon the binder strip already mentioned, but it is necessary to be able to remove the pin to permit renewal of binders. The pin therefore is comparatively loose in its mounting and should be braced by bearings of greater width than the thickness of the plates. It is a further object of our present invention to provide a pair of washers for each plate, one above and the other below and extend a vertical tube through these washers and the associated plate to define a bearing of considerable length for the binder pin.

It is necessary to provide some connection between the gang of boxes and the box lifter rod extending upwardly from the box motion. As shown hereinafter we bend sheet metal into angle form and cut an elongated notch along the bent edge thereof to receive that part of the rear wall of the bottom cell which extends below the bottom plate of the lowest cell. The bracket thus formed is welded to the adjacent plate and wall and may be perforated to receive attaching connections for the top of the box lifter rod.

With these and other objects in view which will appear as the description proceeds, our invention resides in the combination and arrangement of parts hereinafter described and set forth.

In the accompanying drawing, wherein a convenient embodiment of our invention is set forth,

Fig. 1 is a top plan view of a shuttle box made according to our present invention, parts being in section,

Fig. 2 is a front elevation of the multi-cell box shown in Fig. 1,

Fig. 3 is an end elevation viewed from the center of the loom and taken in the direction of arrow 3, Fig. 2, parts being in section,

Figs. 4 and 5 are detailed vertical sections, respectively, on lines 4—4 and 5—5 of Fig. 1,

Fig. 6 is a detail vertical section on line 6—6 of Fig. 2, and

Fig. 7 is a view similar to the left end of Fig. 1 showing a modified tongue and guide plate.

Referring to the drawing, we have shown a two-cell shuttle box but it is to be understood that the construction set forth hereinafter can be extended to boxes not necessarily limited to two cells. The cells C are formed of three identical

plates 10 spaced apart vertically and disposed horizontally when the shuttle box is in the loom. Each plate has extending from the rear edge thereof a plurality of tenons 11 which project through vertical relatively narrow sheet metal backs 12. There will be a back for each plate and the back for the top plate will project above the latter as at 13 so that the tenons 11 may extend through slots 14 formed in the backs. By this construction bending of the metal is avoided and the two parts so connected may be flat and the tenons welded to the four sides of the slots through which they extend.

Extending along the front outer corner of the shuttle box is a tongue wall 15 held to the plates 10 by tenons 16 thereon which project into and are welded to the wall, thus keeping the plates spaced vertically. Tapped holes 17, one above the top plate 10 and the other below the bottom plate, pass through the wall 15. Bolts 18 are threaded into holes 17 and are held by check nuts 19 bearing against the rear of wall 15. A tongue plate 20 extends vertically along the front face of wall 15 and is held thereto by the heads 21 of the bolts. The outer vertical edge of the tongue plate is formed with a guide tongue 22 to fit a lay carried guide plate indicated in dot and dash lines in Fig. 1 at 23.

As shown in Fig. 2 the right hand edge of the tongue plate 20 is formed with notches 24 to receive the left ends of the feet 25 of the binder springs indicated in dot and dash lines at 26. The binder springs are held in place by bolts 27 which are threaded into the tongue wall 15. The notches 24 will hold the binder springs from falling away from the binders should their bolts work loose, but it should be noted that vibration of the springs due to shuttle boxing will not disturb the setting of the bolts 18 and the tongue plate.

Each plate has a relatively wide inner end 30 from which projects a relatively narrow arm 31. The arms are welded to a vertical binder stop or strip 32 somewhat as set forth in prior Patent No. 1,826,317. We have found it desirable to give additional support to the binder stop and do so by providing blocks 33, one for each cell floor, as shown in Fig. 3.

Each block is welded to the floor with which it is associated and has a tongue 34 which extends into an opening 35 punched in the stop strip 32. A tongue 36 on the arm 31 of each cell also extends into the opening 35 and the two tongues 34 and 36 are welded together and also to the walls of the slot or opening into which they project to be fastened to the part 32. The compartment 40 between the top of a block 33 and the plate 10 immediately thereover is less than the height of the cell, but such a relation has the advantage of adapting the compartment 40 for reception of the reduced end of the binder B, as indicated in Fig. 2.

Extending vertically along the front and outer end of the box is a binder pin 45 on which the binders B pivot. This pin extends through forward extensions 46 on each of the plates 10 and also through specially formed bearings illustrated more particularly in Fig. 4. Each of these bearings comprises upper and lower washers 47 and 48, respectively, through which extends a tube 49 having a vertical bore proportioned to receive the pin 45. The washers, tube 49 and adjacent portions of the plate 10 are all welded together so that the bearing is held rigidly in position and is of sufficient height to provide ample bearing space for the binder pin.

In order that the box may be lifted when placed in the loom we attach thereto a bracket 50 formed of a flat sheet metal plate having a vertical part 51 from which is bent a horizontal attaching ledge 52. As shown in Fig. 6 we cut an elongated notch 55 along the upper rear bent edge of the bracket of a sufficient depth to receive that part 56 of the lowest back member 12. The ledge 52 lies close to and is welded to the lowest plate 10, while the depending flange 56 is welded into the notch 55 to provide a rigid construction by which the lifting force of the box lifter rod may be transmitted to the shuttle box, by a box lifter rod 60.

Fig. 7 shows a tongue plate 65 with a tongue 66 wider than tongue 22 to fit a guide plate different from that shown at 23 and being part of a different type of loom. The part of the tongue plate 65 for attachment to the shuttle box will be substantially similar to the corresponding part shown in Fig. 2, the chief difference being the size to fit a different lay carried guide 67. The main body of the shuttle box will remain the same but there will be a set of different tongue plates from which the correct one for a given style of loom is chosen.

While we have described the tongue plate for the outer end of the shuttle box, it is to be understood that a similar tongue plate 70 is used for the inner end of the box, plate 70 being removable and having the essential characteristics of plate 20 except that the spring receiving notches may be omitted. There will also be a set of plates 70 with different tongues for the purpose described in connection with plate 20.

From the foregoing it will be seen that we have provided a multi-cell shuttle box formed of sheet metal and so constructed as to have removable tongue plates, thereby adapting the shuttle box for use in various types of looms employing the same size shuttle but with differently formed box guide plates. It will further be understood that this construction permits the renewal of worn tongue plates. The construction of the tongue plate is such that the binder springs can be held to the shuttle box without disturbance due to vibration when the shuttle is boxed, and the notches in the tongue plate serve to hold the foot of the spring should the screw for the latter work loose. It will also be seen that the blocks secured to the forwardly projecting arms of the horizontal plates 10 give additional support to the binder stop or strip, the blocks having tongues which fit into said strip and being welded thereto as well as to the arms. Also, the binder pin passes through a bearing of durable construction including washers located above and below plate 10 and surrounding a vertical tube, the parts being welded together to afford substantial support for the binder pin. Although we have shown the blocks as located on the tops of certain of the plates 10, yet we do not wish to be limited to this location of the blocks. The bracket 50 is specially constructed to receive the lower edge of the bottom back 12.

Having thus described our invention it will be seen that changes and modifications may be made therein by those skilled in the art without departing from the spirit and scope of the invention and we do not wish to be limited to the details herein disclosed, but what we claim is:

1. In a sheet metal multi-cell shuttle box for looms, a plurality of vertically spaced horizontal plates, means to hold the outer ends of the plates in spaced vertical relation, additional means to hold the rear portions of the inner ends of said

75

plates in vertical spaced relation, a box mouth forming wall extending vertically in front of and spaced forwardly from said additional means and secured to the plates, forwardly projecting extensions from the plates lying in front of said wall, a vertically extending shuttle binder limiting strip of sheet metal spaced forwardly from said wall and having vertically spaced slots therein, the extensions of certain of the plates extending into the slots in said binder limiting strip, and blocks welded to certain of said extensions and extending into corresponding slots in said binder limiting strip to be secured to the latter, each block serving to hold the corresponding extension and binder limiting strip together and also providing a binder space between adjacent extensions of less height than the space between the corresponding adjacent plates.

2. In a sheet metal multi-cell shuttle box for looms, a plurality of vertically spaced horizontal plates, means to hold the outer ends of the plates in spaced vertical relationship, additional means to hold the rear portions of the inner ends of the plates in spaced vertical relationship, a box forming wall extending vertically in front of and spaced forwardly from said additional means and secured to said plates, extensions projecting forwardly from said plates and in front of said wall, a vertical shuttle binder limiting strip extending vertically in front of and spaced forwardly from said wall and secured to said plates and having slots therein for certain of said extensions, tongues formed on certain extensions to project into corresponding slots in said binder

limiting strip and be secured to the latter, and metallic blocks secured to certain of said extensions and having tongues to project into the slots of the binder limiting strip which receive the tongues of the corresponding extensions, the tongues of the blocks being secured to said binder limiting strip, and said blocks defining a binder receiving compartment of less height than the distance between adjacent plates.

3. In a sheet metal multi-cell shuttle box for looms, a plurality of sheet metal horizontally extending vertically spaced plates, means to hold said plates in spaced relation vertically, a binder pivot pin extending vertically through the plates, each plate having a binder pin receiving bearing including a vertical tube extending above and below the plate, and sheet metal elements, one above and the other below and secured to each plate and extending around and secured to the corresponding binder pin bearing tube.

4. In a sheet metal multi-cell shuttle box for looms, a pair of horizontally extending vertically spaced plates, means to hold said plates in spaced vertical relation, a binder pin extending vertically through the plates, and a bearing on each plate for the binder pin, each bearing comprising a pair of sheet metal washers welded to the corresponding plate one above and the other below said plate, and said bearing also including a vertically extending metallic tube through which the binder pin extends and to which said washers are welded.
